Specification for Design.

Patented Apr. 26, 1921.

Application filed February 15, 1921. Serial No. 445,264. Term of patent 14 years.

To all whom it may concern:

Be it known that I, SAMUEL JAFFE, a citizen of the United States, residing in the city of Richmond, in the county of Wayne, State of Indiana, have invented a new, original, and ornamental Design for Radiator-Caps, of which the following is a specification, reference being had to the accompanying drawings, forming part thereof.

Figure 1 is a top plan view of a radiator cap showing my new design.

Fig. 2 is a side elevation.

Fig. 3 is a central longitudinal section thereof.

I claim:

The ornamental design for a radiator cap, as shown.

In testimony whereof I have hereunto subscribed my name to this specification in the presence of two subscribing witnesses.

SAMUEL JAFFE.
